EGG-TESTER.

1,210,733.

Specification of Letters Patent.

Patented Jan. 2, 1917.

Application filed July 12, 1915. Serial No. 39,367.

To all whom it may concern:

Be it known that I, CLAYTON VON CULIN, a citizen of the United States, residing at New York, in the county of New York and State of New York, have invented certain new and useful Improvements in Egg-Testers; and I do declare the following to be a full, clear, and exact description of the invention, such as will enable others skilled in the art to which it appertains to make and use the same.

This invention relates to new and useful improvements in egg testers and more particularly to electric egg testers and the primary object of my invention is to provide an improved device of this character wherein the egg receiving opening in advance of the light, is of a variable size, and has its center alined permanently with the light.

A further object of the invention is to provide a device of this character which is simple and durable in construction, inexpensive to manufacture and one which will be very efficient in operation.

With these and numerous other objects in view, my invention consists of certain novel features of construction, combination and arrangement of parts which will be herein referred to and more particularly pointed out in the specification and claims.

In the accompanying drawings, Figure 1 is a front view of my improved egg tester; Fig. 2 is a side elevation of the same; Fig. 3 is an enlarged front view of the light and means for varying the size of the egg receiving opening, partly in section; Fig. 4 is a horizontal section on the line 4—4 of Fig. 1; Fig. 5 is a central vertical longitudinal section on line 5—5 of Fig. 1; Fig. 6 is a detail perspective of the vertical upright as attached to one of the poles of the battery; and Fig. 7 is a detail perspective of the supporting bracket that holds the lamp.

In describing my invention, I shall refer to the drawings in which similar reference characters designate corresponding parts throughout the several views and in which numeral 1 designates the battery, which in this instance is shown of the ordinary dry cell type having the two poles 2 and 3 projecting therefrom in the manner usual in devices of this character.

The lighting source of this egg tester consists of an incandescent electric lamp 4 centrally disposed in a reflector 5 as clearly

shown in Fig. 4 of the drawings. Around the reflector 5 is a rectangular shaped block which forms a casing 6 which has a recessed open front covered by a face plate 8, which has therein an egg receiving opening 8'. 60 This face plate 8 consists of a sheet of any desired material, for instance pasteboard, which is substantially rectangular in shape and has rearwardly turned upper and lower edges forming attaching flanges 9 with vertically directed ends 10 adapted to be positioned on the rearwardly turned side edges 11, which constitute additional attaching flanges. The upper and lower flanges 11 are spaced apart as shown at 12 for a purpose to be hereinafter more fully set forth. 70

The flanges of the face plate 8 are secured to the sides of the casing 6 in such a manner that the face plate 8 will be spaced a short distance from the front of the said 75 casing, so that a pair of substantially rectangular sliding members may be positioned therebetween. These sliding members which are numbered 13 and 14, are substantially rectangular in shape, and are of a slightly 80 shorter length than the length of the face plate and casing to allow them to slide therebetween. Coacting apertures 15 and 16 are formed in the said slides, and when the same are in operative position, the two opposed semi-circular edges of the said apertures 15 and 16 are adapted to form egg receiving faces upon reducing the size of the egg receiving aperture 8' in the face plate 8. 85

The slide members 13 and 14 have formed 90 on their outer edges integrally projecting tabs 17 which are adapted to project laterally from the sides of the face plate 8, through the openings 12 therein as clearly shown in Figs. 1 and 3 of the drawings. By 95 this means, the sliding members may be very easily and simply operated to accomplish their purpose of reducing and enlarging the size of the egg receiving opening.

This egg tester is adapted to be secured 100 in contact with the battery 1, and adjustably positioned with respect thereto by means of an L-shaped supporting bracket 18. This L-shaped supporting bracket 18 has an aperture 19 in its upper end which is adapted 105 to engage the projecting end of the reflector 5 that surrounds one terminal of the electric lamp 4. The opposite end of the bracket 18 is pointed as shown at 20 and is engaged with the back of the casing 7 as shown in 110

Fig. 5 of the drawings. The base portion of this L-shaped bracket 18 is provided with a longitudinally extending slot 21, through which the pole 2 of the battery is adapted to project, and said pole is firmly held in contact therewith by means of the nut 22 which engages the same and clamps the base portion of the bracket thereto. By this means, it will be noted, that the supporting bracket 10 may be positioned in various longitudinally adjustable positions with respect to the top of the battery 1 for a purpose to be herein-after more fully described. This attaching bracket 18 is formed of a piece of spring metal which has a certain amount of spring or resiliency to allow the same to be moved backward and forward when in operative position.

Projecting upwardly from the pole 3 of the battery is a vertical support 23 which has extending laterally therefrom, a slotted attaching foot 24 which is connected to the pole 3 of the battery by means of the securing cap 25. This vertical upright 23 which is adapted to form a circuit closing contact with the outer terminal lamp 4, is of the same height as the bracket 18 which supports the said lamp.

In operation, when the parts of this device are assembled, as shown in Figs. 1 and 20 of the drawings, and it is desired to test an egg, the egg is held in front of the egg receiving opening 8' in the face plate 8, and the said plate and casing move backward 30 until the end terminal of the lamp 4 contacts with the vertical upright 23, whereby the circuit will be completed and the lamp lighted. The method of testing an egg when held in this position is too well known to need any 35 further explanation. Upon releasing the casing, the lamp will be thrown out of contact with the upright 23, owing to the fact that the supporting bracket 18 is formed of spring metal and hence, while the lamp is lighted, it will be under a constant pressure 40 to return to its normal inoperative position. The above described engagements of the support, and the vertical upright, with the poles of the battery 1, allow various adjustments of this device as will be obvious.

A most essential feature of my invention relates to the operation of the coacting apertured slides 13 and 14 which are positioned between the face plate 8 and the casing 7. 55 If the egg which is held over the egg receiving aperture 8' in the face plate 8 is too small for said aperture, all that it is necessary to do to regulate the aperture to any sized egg, is to pull laterally on the 60 projecting tabs 17 at the side of the face plate, whereby the egg engaging faces 15 and 16 of the slides 13 and 14 will be drawn together and will adjust themselves to the size of the egg. It will be noted in this 65 adjustment that no matter what size the

aperture is made, the light or lamp 4 which is positioned just behind the aperture will always be centrally alined with the said opening. This is an essential feature of my invention as in no case will the light 70 be reflected from one side but will always be positioned in the exact center behind the egg.

The direct and permanent alinement of the light with the center of the aperture over which the egg is disposed, is necessary in a device of this character owing to the fact that the electric lamp used is so small, that even with the help of the reflector 5, it is necessary to position the same 75 directly behind the egg, so that the full force of the direct rays of light will be projected therethrough. If the lamp were positioned at one side of the aperture, while it would be possible to in a manner test the egg from the light in this position, it is an obvious and necessary improvement to position the light directly behind the egg whereby a much better and more efficient direction 80 of the rays of light may be obtained.

When the lamp is positioned in the manner above described, owing to the fact that the same is always disposed centrally behind the egg no matter what size the egg may be, it will be possible for the operator or observer to easily and carefully examine the 90 egg in the manner described.

From the foregoing description, of the construction of my improved egg tester, the manner of applying the same to use and the 95 operation thereof will be readily understood and it will be seen that I have provided a simple, inexpensive and efficient means for carrying out the objects of this invention.

I claim:—

1. An egg tester comprising a casing having in its front an egg receiving opening, a source of light in said casing in permanent alinement with the axis of said opening, and a pair of oppositely moving slides adjacent the rear side of said front of the casing, each of said slides having an opening, which openings are adapted for total or partial registration with each other and with said opening in the casing, whereby 110 the active area of the latter may be varied to permit eggs of different sizes to be tested and to always aline the eggs with the source of light.

2. An egg tester comprising a rectangular block having in its front face a recess and having at substantially the center of said recess a source of light, a pair of flat rectangular overlapped slides extending over said recess in sliding engagement with the 120 front face of the block, the outer upright edges of said slides having integral operating tabs projecting beyond the edges of the block while the upper and lower edges of said slides are disposed substantially flush 125 130

with the corresponding edges of the block, a rectangular front plate in front of the slides and equipped with rearwardly extending flanges secured to the edges of the block, certain of said flanges extending above and below the aforesaid tabs, said plate having an egg receiving opening whose axis is permanently alined with the source of light, and said slides having openings 5 for total or partial registration with each other and with the aforesaid opening to per-

mit eggs of different sizes to be tested and to always aline said eggs with the source of light.

In testimony whereof I have hereunto set 15 my hand in presence of two subscribing witnesses.

CLAYTON VON CULIN.
